UNITED STATES PATENT OFFICE.

ALBERT C. ASPER, OF KANSAS CITY, KANSAS.

WORK-HOLDING APPARATUS.

Application filed April 18, 1927. Serial No. 184,649.

My invention relates to improvements in work holding apparatus. It is particularly well adapted for properly positioning and securely holding objects, such as bearing 5 caps, for surfacing with an abrading device, such as a file, or for resurfacing the same to compensate for wear occasioned by use.

One of the objects of my invention is to provide an apparatus of the kind described, 10 which is simple, cheap, durable, not liable to get out of order, which is easy to adjust and operate, and which will ensure that the new surface produced in the abrading operation will be parallel to the original surface, there- 15 by providing a proper fitting between the cap and the shaft with which it co-operates.

A further object of my invention is to provide novel means for effecting proper pos- 20 tioning of the work, and novel means for limiting the action thereon of the abrading device.

Still another object of my invention is the provision of novel means for tightly clamp- 25 ing and holding the work in the position to which it may be adjusted preliminary to the abrading operation.

The novel features of my invention are hereinafter fully described and claimed.

In the accompanying drawings, which il- 30 lustrate the preferred embodiment of my in- vention,

Fig. 1 is a vertical central sectional view on the line 1—1 of Fig. 2, of my improved apparatus.

Fig. 2 is a plan view of the same, shown mounted on a suitable support.

Fig. 3 is a side elevation of the same.

Fig. 4 is a section, partly broken away, on the plane of the line 4—4 of Fig. 3, the stop 40 gage and file being removed, and the pos- 95 titioning gage substituted therefor.

Fig. 5 is a side elevation of the oscillatory work supporting member.

Fig. 6 is a reduced plan view of the base 45 and a portion of its support.

Fig. 7 is an under plan view of the posi- 50 tioning gage.

Fig. 8 is a top view of the member shown in Fig. 5.

Fig. 9 is a top view of the cam lever.

Fig. 10 is a top view of the stop gage.

Fig. 11 is a cross section of the same on the line 11—11 of Fig. 10.

Similar reference characters designate 55 similar parts in the different views.

The apparatus is provided with a base

comprising a member 1, which is adapted to be supported upon and fastened by bolts 2 to a bench or other suitable support 3.

The member 1 is provided with radial up- 60 standing arms 4, the upper ends of which terminate in a horizontal externally threaded ring 5, on which is fitted an internally threaded, revoluble and vertically movable ring bearing 6, the upper side of which is 65 provided with a horizontal plane annular surface 7, which is adapted to support a stop gage 8, which may be of any suitable form, and which in the drawings is shown as rectangular and provided with a central 70 square opening 9, and four depending corner legs 10, which are adapted to rest upon the annular surface 7, and which engage the inner periphery of the bearing 6, as shown in Figs. 1, 2 and 3. 75

The stop gage 8 has fastened to its upper side, at opposite sides respectively of the opening 9, two parallel horizontal flat hardened steel plates 11, the upper sides of which form stop surfaces, which, when the gage 8 80 is mounted on the bearing 6, are both in the same plane and parallel with the annular surface 7.

The top plates 11 are adapted to engage and limit the downward movement of an 85 abrading device, such as a file 12, which is being used for resurfacing the flat inner side portions of a bearing cap 13, which it may be desired to resurface to enable it to properly co-operate with the shaft, not shown, with 90 which it is to be used.

For supporting and holding properly positioned the cap 13, during the filing opera- 95 tion, I provide the following described work supporting means comprising a work sup- 100 porting member having a cylindrical head 14, provided with a flat upper side having in it a central rectangular slot 15, Fig. 8, the ends of which respectively communicate with two diametrically opposite vertical slots 16, provided respectively in opposite sides of the head 14.

The work supporting member is provided with a central vertical tube 17, the upper externally threaded end of which is fitted in a 105 central threaded vertical hole in the closed lower end of the head 14.

In order that the work supporting mem- 110 ber may be adapted for universal adjustment, the lower portion of the head 14 has a spher- ically formed peripheral portion 18, which is mounted and adapted for universal move-

ment in a correspondingly shaped seat 19, provided in the upper side of the base member 1 concentric with the axial center thereof.

- 5 For fastening the work supporting member 14 in the position to which it may be adjusted, it is provided with an abutment, which may comprise a nut 20, which is fitted on the threaded lower end of the tube 17, 10 and which is adapted to bear against the lower end of a central vertical tube 21, the upper end of which is threaded and fitted in a central threaded hole provided in the base member 1.
- 15 The upper side of the nut 20 is spherically concave, the arc of which has the same center as the spherically convex portion 18 of the head 14. The lower abutting end of the tube 21 is spherically convex, as is the 20 lower end of a sleeve 22 which is adapted to bear against the nut 20, and which is vertically slidable and non-rotatable on the tube 21.

For holding the sleeve 22 from rotation, 25 it may have fastened to it one end of a brace bar 23, the other end of which may be fastened to the bench 3, Fig. 4.

For forcing the sleeve 22 downwardly against the nut 20, so as to retain the work 30 holding member in its adjusted position, I provide a cam lever 24, Figs. 3, 4, and 9, which is provided at one end with a tubular portion 25, which is revolvably fitted on the tube 21, and the lower flat end of which is 35 adapted to bear against the upper end of the sleeve 22. The upper end of the tubular portion 25 is provided with two semi-circular cam surfaces 26, which are adapted to respectively engage corresponding cam surfaces 27 on the lower side of the base member 1.

By turning the cam lever 24 counter clockwise, as viewed from above, the sleeve 22 will be forced downwardly into tight engagement with the nut 20, thereby holding the latter and with it the work supporting member from movement.

For supporting the work, such as the cap 13, upon the head 14, there may be mounted 50 upon the top of the head 14, at opposite sides respectively of the slot 15, two parallel channel bars 28, Figs. 1 and 2, upon which the bottom side of the cap 13 rests.

For tightly clamping the work 13 upon 55 the parallel bars 28, I provide a horizontal clamping bar 29, which is adapted to be disposed in the semi-cylindrical portion of the upper side of the cap 13 and which has mounted on it at opposite ends respectively of said cap two links 30, Figs. 1 and 4, which support a cross bar 31, which is centrally pivoted by a horizontal pin 32 to the upper end of a vertical rod 33, which extends through the tube 17 and which, outside the tube, has a threaded portion on which is

fitted a hand wheel 34, the upper side of which bears against the lower end of the tube 17.

The links 30 are disposed respectively at opposite sides of the rod 33. The bar 31 is 70 slidable in the slots 16.

For normally forcing the rod 33, and with it the bar 31, upwardly, a coil spring 35 encircles the rod 33 and has its lower end bearing against an annular shoulder 36 on 75 the inner side of the tube 17. The upper end of the spring 35 bears against a circular inverted cup shaped shield 37 on the rod 33 in the head 14, the upper side of said shield bearing against a head with which the 80 upper end of the rod 33 is provided. When the cap 13 has been filed and removed, the spring 35 will keep the wheel 34 against the tube 17.

The head 14 is provided with peripheral 85 openings 38 through which may pass filings which enter the head 14 through the slot 15 and which are deflected by the shield 37 through the openings 38, thus preventing 90 the filings getting into the seat 19.

For preventing the filings from entering the threaded connection between the base ring 5 and the bearing 6, I provide a funnel shaped deflector 39, the smaller lower end of which projects into the ring 5, and the 95 larger upper end of which has an annular peripheral flange 41, which extends into an inner annular groove 42 in the bearing 6.

For properly positioning the work with 100 respect to the stop gage 8, there may be provided a positioning gage 43, Figs. 4 and 7, which is provided with four radial legs 44, which are adapted to rest upon the annular surface 7, when the stop gage 8 is removed, and which are adapted to engage the inner 105 periphery of the bearing 6, in the same manner as do the legs 10 of the stop gage 8.

The legs 44 are of such length and height that the plane bottom side, of the gage 43, will be the same distance from the plane of 110 the annular surface 7 as is the distance from said annular surface 7 to the plane of the upper sides of the stop plates 11, when the gage 8 is mounted in operative position on the bearing 6, as hereinbefore described.

The peripheral lower portion of the bearing 6 is provided with graduations 45, which may represent respectively thousandths of an inch in vertical movement of the bearing 6 and with which co-operates an 115 upstanding pointer 46, the lower end of which is fastened to the base 1, Figs. 3, 4 and 6.

In the operation of the invention, the work 13 is fastened on to the channels 28, 120 in the manner hereinbefore described, the nut 20 being tightened against the tube 21 just sufficiently to hold the head 14 with a light pressure in the seat 19.

The positioning gage 43 then has its flat 125

- bottom side placed upon the work 13 with the legs 44 separated from the annular surface 7. The cam lever 24 is disposed in the released position, after which the bearing 6, is turned on the ring 5 so as to move upwardly, and the rod 33 is tapped laterally at different sides, until the portions of the legs 44, which are to engage the bearing surface 7 are just barely clear of said surface. 65
- 10 The adjustment is made until light can barely be seen between each leg 44 and the adjacent portion of the annular surface 7. The lever 24 is then swung to the tightening position thereby forcing the sleeve 22 tightly against the nut 20, thereby fastening the work supporting means and the work 13 in their proper adjusted position. 70
- 15 The positioning gage 43 is then removed, and the stop gage 8 substituted therefor on the annular surface 7. At this time the upper side of the work 13 will be substantially in the plane of the upper sides of the stop plates 11. 75
- 20 The bearing 6 is then turned so as to be lowered the desired distance, that it is designed to file away the upper side of the work 13. This amount may be determined by observation of the pointer 46 and the graduations 45. 80
- 25 30 The file 12, or other abrading device, may then be used to dress away the upper side of the work 13. The abrading operation is continued until the file 12 rests upon both plates 11, when the file is disposed at any 85
- 35 point over the work. The new surfaces, thus produced on the work will be exactly parallel with the original surface, so that the cap will properly fit the shaft with which it has been used when it is applied to 90
- 40 the shaft. 95
- I do not limit my invention to the structure shown and described, as many modifications, within the scope of the appended claims, may be made without departing 100
- 45 from the spirit of my invention. 105
- What I claim is:—
1. In an apparatus of the kind described, a bearing having a plane upper surface, a gage revoluble thereon having an upper plane stop surface parallel with said surface and adapted to engage and limit the downward movement of an abrading device operating on the work, and means adapted for universal adjustment of and for supporting the work in a position projecting above said stop surface. 110
  2. In an apparatus of the kind described, a bearing having a plane upper surface, a gage revoluble thereon having an upper plane stop surface parallel with said surface and adapted to engage and limit the downward movement of an abrading device operating on the work, and means adapted for universal adjustment of and for supporting the work in a position projecting above said stop surface. 115
  3. In an apparatus of the kind described, a support, a bearing revoluble thereon and having threaded engagement therewith and provided with a plane upper surface, a gage revoluble on said surface and having an upper plane stop surface parallel with said surface and adapted to engage and limit the downward movement of an abrading device operating on the work, and means adapted for universal adjustment of and for supporting the work in a position projecting above said stop surface. 120
  4. In an apparatus of the kind described, a support, a bearing vertically adjustable thereon having a plane upper surface, a gage revoluble on said surface and having an upper plane stop surface parallel with said surface and adapted to engage and limit the downward movement of an abrading device operating on the work, and means adapted for universal adjustment of and for supporting the work in a position projecting above said stop surface. 125
  5. In an apparatus of the kind described, a bearing having a plane upper surface, a support on which the bearing is revoluble and has threaded engagement therewith, a gage revoluble on said surface and having on its upper side two stop surfaces at opposite sides respectively of axis of said gage and disposed parallel with the first named surface and adapted to engage and limit the downward movement of an abrading device operating on the work, and means adapted for universal adjustment of and for supporting the work between and projecting above said stop surfaces. 130
  6. In an apparatus of the kind described, a support, work supporting means adapted for universal adjustment thereon and provided with an abutment, a sleeve on said support and adapted to bear against said abutment, bracing means connecting said sleeve with said support for holding the sleeve from turning, and tightening means between said support and said sleeve for forcing the latter against said abutment. 135
  7. In an apparatus of the kind described, a support, work supporting means adapted for universal adjustment thereon and provided with an abutment, a sleeve slidable and non-rotatable on said support and adapted to bear against said abutment, and tightening means for forcing said sleeve against said abutment. 140
  8. In an apparatus of the kind described, a support having a cam surface and a seat, work supporting means adapted for universal adjustment on said seat and having an abutment, a sleeve on said support adapted

to bear against said abutment, and a tightening member revoluble on said support and bearing against said cam surface and said sleeve for forcing the latter against said abutment.

9. In an apparatus of the kind described, a support having a cam surface and a seat, work supporting means adapted for universal adjustment on said seat and having an abutment, a sleeve non-rotatably mounted on said support and longitudinally movable thereon against said abutment for forcing said work supporting means against said seat, and a tightening member revoluble on said support between said cam surface and said sleeve and adapted when revolved in one direction to engage said cam surface and

said sleeve for forcing the latter against said abutment.

10. In an apparatus of the kind described, a ring bearing having an annular upper plane surface, a gage having an opening therethrough and revoluble on said annular surface and having an upper plane stop surface parallel with said annular surface and adapted to engage and limit the downward movement of an abrading device operating on the work, and means adapted for universal adjustment of and for supporting the work in said opening and projecting above said stop surface.

In testimony whereof I have signed my name to this specification.

ALBERT C. ASPER.
